Inventor:

Georg Müller.

UNITED STATES PATENT OFFICE.

GEORG MÜLLER, OF NUEREMBERG, GERMANY, ASSIGNOR TO PFISTER & LANGHANSS, OF NUEREMBERG, GERMANY.

FLOW-OFF AND OVERFLOW DEVICE FOR BATHING TUBS.

Application filed May 12, 1924. Serial No. 712,907.

To all whom it may concern:

Be it known that I, GEORG MÜLLER, a German citizen, and residing at Nuremberg, Germany, have invented certain new and useful

- 5 Improvements in Flow-Off and Overflow Devices for Bathing Tubs (for which I have made application in Germany on May 17th, 1923, Patent No. 395,031), of which the following is a specification.
- 10 This invention relates to an improved flow-off and overflow device for bathing tubs, and its novelty consists in the arrangement thereon of an integral water seal main body comprising a lateral branch for its attachment to a waste pipe and so constructed that said branch can be located to direct either to the left side or to the right side of said bathing tub.
- 15 The accompanying drawing illustrates a constructional form of the subject matter of the invention: Figs. 1 and 2 are respectively a fragmentary side view and end view of a bathing tub fitted with the improved arrangement.
- 20 The water seal main body *a* has an internal partition wall in a way known in the art and comprises a screw-threaded lateral branch *b* for its attachment to a waste pipe (not shown), it being arranged at right angles to the axis of the flow-off pipe *d* of the bathing tub, while it is further fitted at its lower end with a screw-threaded front branch *c* for the reception of a cleaning screw *x* and with a screw-threaded rear branch *c'* for its being joined to the flow-off pipe *d*, said two latter branches having equal

screw-threads and lying in line with the axis of said flow-off pipe, while an upper screw-threaded branch *e* on said main body serves for its attachment to the overflow pipe *f* of the bathing tub.

Said main body *a* can be connected with flow-off pipe *d* either by means of its front branch *c* or by means of its rear branch *c'* (as illustrated) in such a way that its lateral branch *b* is directed either to the left side (as shown) or to the right side of the bathing tub.

What I claim is:—

In a flow-off and overflow device for bathing tubs: the combination with a flow-off pipe and an overflow pipe both attached to the bathing tub, of an integral water seal main body arranged at right angles to the axis of said flow-off pipe and comprising a screw-threaded lateral branch and a screw-threaded upper branch for its attachment to a waste pipe and to said overflow pipe respectively and an equally screw-threaded front and rear branch at its lower end both lying in line with said flow-off pipe, either of said two latter branches being joined with said flow-off pipe, and a detachable cleaning screw on the other free branch, substantially as and for the purpose set forth.

In testimony whereof I have hereunto set my hand in the presence of two subscribing witnesses.

GEORG MÜLLER.
